Floyd W. Harris
ATTORNEY

UNITED STATES PATENT OFFICE

LYMAN K. STAFFORD, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

DERRICK LEG WITH REINFORCING MEMBER

Application filed May 27, 1929. Serial No. 366,162.

My invention relates to derricks used in the well drilling industry and in particular to a type of leg construction for use with derricks of this class in which a reenforcing member is attached to the leg.

Derricks are used during the drilling of a well for the purpose of handling the various casings, drill pipe, and other equipment used in this operation. The drilling equipment often weighs many tons and it is customary to support the weight thereof by the crown-block which is located at the top of the derrick structure. The crown-block is supported mainly by the derrick legs which are often strengthened by reenforcing members so as to better support the weight. When so strengthened it is desirable to have the reenforcing members support a portion of the weight of the crown-block so as to relieve the derrick legs of this weight. This further strengthens the derrick, which must be constructed heavily enough to withstand the stresses to which it is subjected during the drilling of the well.

After the well is drilled and the pumping operation begins the derrick is not subjected to such great stresses, as the pumping equipment is relatively light in weight as compared to the drilling equipment. The derrick may therefore be of lighter construction during the pumping of the well and it is customary to remove the reenforcing members after the drilling is completed.

It is an object of my invention to provide a reenforcing member of novel form which may be attached to the derrick legs during the drilling operation to provide a strong construction and which may be easily removed therefrom, so as to provide a lighter construction during the pumping operation. This provides a great economy in the construction of derricks, as the derrick need only be of heavy enough construction for the pumping operation and may be strengthened for the drilling operation by means of the

reenforcing members. After the reenforcing members have been used for one drilling operation they may be removed and used on another derrick.

It is another object of my invention to provide a novel means of securing the reenforcing members to the derrick legs so that they will be rigidly secured thereto but may be easily removed when it is so desired.

Further objects of my invention will appear hereinafter.

In the accompanying drawing I have shown a device of my invention.

Fig. 1 is a side view showing a derrick leg with a reenforcing member of my invention attached thereto.

Fig. 2 is a partial section taken on the line 2—2 of Fig. 1, showing the manner of attaching the reenforcing member at its upper end.

Fig. 3 is a partial section taken on the line 3—3 of Fig. 1, showing the manner of attaching the reenforcing member at its lower end.

Fig. 4 is a sectional view taken on the line 4—4 of Fig. 1, showing the manner of attaching the reenforcing member to the derrick leg.

Fig. 5 is a view showing the appearance of a special washer used in attaching the reenforcing member to the derrick leg.

Referring to the drawings, Fig. 1 shows a permanent derrick leg 10 to which are secured derrick brace members such as base channels 11, reenforcing angles 12, girts 13, and water table channels 14. The derrick leg 10, shown in the sectional view in Fig. 4, is composed of a semi-tubular portion 16 constituting a major part of a cylinder, and integrally formed flanges 18 extending outwardly from the edges thereof. The flanges 18 have outer faces 19 which are at right angles to each other and which provide surfaces on which to attach the derrick members.

Secured to the derrick leg 10 on the inner side thereof is a removable reenforcing leg member 20 of my invention. I prefer to fur-

nish the reenforcing member 20 with the same cross-section as the derrick leg 10 so that they may be made from the same stock material and may be easily secured together to form a strong construction. In Fig. 4 is shown a section of the reenforcing member 20 consisting of a tubular portion 21, and integrally formed flanges 22 extending outwardly from the tubular portion 21, which flanges have right angled faces 23.

As shown in Fig. 4, the reenforcing member 20 is attached to the derrick leg 10 with the internal angles of the flanges 18 and 22 adjacent and with edges 25 and 26 of the flanges 18 and 22 spaced a small distance apart. This is to permit access to the space between the derrick leg 10 and the reenforcing member 20 when securing derrick members to the flanges 18 of the derrick leg 10.

Between the edges 25 and 26 of the flanges 18 and 22 a bolt 27 is passed, on which are V blocks or washers 28 which are best shown in Fig. 5. Each of the washers 28 has a central opening 29 and a right angled groove or V on a face thereof. The inclined faces 31 of the groove engage the right angled faces 19 and 23 of the flanges 18 and 22 and when a nut 32 on the bolt 27 is tightened a wedging action occurs which clamps the edges 25 and 26 of the flanges 18 and 22 tightly against the bolt 27. This provides an independent clamping means which rigidly secures the derrick leg 10 and the reenforcing member 20 together but allows them to be readily separated when the nut 32 on the bolt 27 is loosened, without disturbing the derrick members which are secured to the flanges of the permanent leg member 10.

As best shown in Fig. 2, a supporting plate 34 is attached to the water table channels 14 by bolts 35 and has a grooved opening 36 in a lower face thereof, into which the upper end of the reenforcing member 20 is inserted. The grooved opening 36 holds the end of the reenforcing member 20 in place under the supporting plate 34 so that the weight of the water table and associated apparatus is supported thereby.

As best shown in Fig. 3, a lifting-jack is associated with the lower end of the reenforcing member, said lifting-jack including a lifting-head 37 having an upper cylindrical portion which is inserted with a friction-tight fit into the opening formed by the tubular portion of the reenforcing member 20, and a flange 38 formed on its lower portion forming a shoulder 39 which contacts the lower end of the reenforcing member 20 and provides a support therefor. The friction-tight fit of the lifting-head in the member 20 is made possible by reason of the fact that the semi-tubular portion of said member 20 forms a major part of a cylinder and thus retains said head against transverse movement. The head 37 has a threaded central

opening 40 into which an adjusting jack-screw 42 is threadedly inserted. The jack-screw 42 has a convex foot 43 which fits into a concavity 44 formed in the upper surface of a base block 45 supported on a foundation block 46.

This jack arrangement provides a means for adjusting the amount of load to be carried by the reenforcing member 20, since when it is screwed out of the head 37, the head 37 is moved upward, which places the reenforcing member 20 in compression and increases the load thereon. After the load on the reenforcing member 20 has been adjusted, shims 47 are placed between the head 43 and head 37 so as to relieve the thrust on the threads of the jack.

It will be seen that the reenforcing member 20 may be quickly attached or removed from the derrick since in attaching it there-to it is only necessary to insert the upper end thereof into the grooved opening 36, secure it to the derrick leg 10 by the attaching means or bolt 27 and washers 28, and adjust the load thereon by the jack. The derrick is then reenforced for the heavy drilling work. When the heavy drilling work is completed and the relatively light pumping work is begun, the reenforcing member 20 may be easily and quickly detached from the derrick leg 10 and used elsewhere.

I claim as my invention:

1. In a derrick, the combination of: a leg structure comprising a permanent leg member and an opposed relatively aligned removable leg member, each having a medial longitudinal body portion and integral transversely diverging longitudinal flanges, said leg members being disposed to face each other to form a hollow column; brace members associated with said permanent leg member; securing means for securing said brace members to the flanges of said permanent leg member; and attaching means for removably securing said removable leg member to said permanent leg member, said attaching means being independent of said securing means whereby said removable leg member may be removed while said brace members remain secured to said permanent leg member.

2. A combination as defined in claim 1 in which said independent attaching means extends diametrically through said column between said leg members.

3. A combination as defined in claim 1 in which said independent attaching means comprises opposed blocks embracing the adjacent flanges of said leg members and a bolt means extending diametrically through said column between said leg members and functioning to draw said blocks towards each other.

4. In a derrick, the combination of: a leg structure comprising a permanent leg member and an opposed relatively aligned removable

able leg member, each having a medial longitudinal body portion and integral transversely diverging longitudinal flanges, said leg members being disposed to face each other 5 to form a hollow column; brace members associated with said permanent leg member; securing means for securing said brace members to the flanges of said permanent leg member; and attaching means for removably 10 securing said removable leg member to said permanent leg member so as to leave a space between said leg members affording access to the interior of said column, said attaching means being independent of said securing 15 means whereby said removable leg member may be removed while said brace members remain secured to said permanent leg member.

5. In a derrick, the combination of: a leg structure comprising a permanent leg member and an opposed relatively aligned removable leg member, each having throughout its 20 length a cross-sectional contour defining a semi-tubular body portion having opposed longitudinal edges and integral transversely diverging longitudinal flanges extending outwardly from said edges, said leg members being disposed to face each other to form a hollow column; clamping means 25 engaging over said flanges so as to leave a space between said leg members; and attaching means extending through said space and said clamping means for removably securing said removable leg member to said permanent 30 leg member.

6. In a derrick, the combination of: a leg structure comprising a permanent leg member and an opposed relatively aligned removable leg member, each having throughout its 40 length a cross-sectional contour defining a semi-tubular body portion comprising a major portion of a cylinder and having opposed longitudinal edges and integral transversely diverging longitudinal flanges extending outwardly from said edges, said leg members being disposed to face each other to form a hollow column; clamping means engaging said 45 flanges in a manner to leave a space between said leg members; and attaching means extending through said space and said clamping means for removably securing said removable leg member to said permanent leg member.

7. In a derrick, the combination of: a leg structure comprising a permanent leg member and an opposed relatively aligned removable leg member, each having a medial longitudinal body portion and integral transversely diverging longitudinal flanges, said 50 leg members being disposed to face each other to form a hollow column; elevating means for adjustably supporting said removable leg member so as to adjust the load on said removable leg member, said elevating means having a lifting head engaging within the 55

body portion of said removable leg member and said body portion being semi-tubular and comprising a major portion of a cylinder so as to prevent lateral displacement of said lifting head; and means for removably securing said removable leg member to said permanent leg member.

In testimony whereof, I have hereunto set my hand at Los Angeles, California, this 20th day of May, 1929.

LYMAN K. STAFFORD.
